UNITED STATES PATENT OFFICE.

YAICHIRO SHIBA, OF SAN JOSE, CALIFORNIA.

COMBINED FINGER RING AND CORD CUTTER.

Application filed February 24, 1923. Serial No. 620,959.

To all whom it may concern:

Be it known that I, YAICHIRO SHIBA, a subject of the Emperor of Japan, residing at San Jose, in the county of Santa Clara and State of California, have invented new and useful Improvements in Combined Finger Rings and Cord Cutters, of which the following is a specification.

This invention resides in the provision of a novel and highly useful combined finger ring and cord cutter in which the device has the appearance of an ordinary ring and is provided with a concealed cutter whereby cord or string such as used in stores for tying packages and bundles may be easily and conveniently severed while the ring is worn on the hand.

An object of the invention is to provide a device of the character described in which the latter is located beneath the setting or ornamental portion of the ring, said ornamental portion or setting of the ring being hinged whereby it may be moved to permit of access to the cutter and moved to lie flat on the ring and conceal the cutter.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a perspective view showing the manner of use of the ring to cut a string.

Fig. 2 is a top plan view of the device.

Fig. 3 is a plan view with the ornamental portion or head of the ring removed.

Fig. 4 is a side elevation of the ring as when the head is closed.

Fig. 5 is a side elevation showing the head raised to permit access to the cutter.

Fig. 6 is a sectional view through the ring.

Fig. 7 is a rear elevation.

In carrying out the invention I provide an ordinary finger ring body portion 1, having an enlargement 2 thereon, on which enlargement the setting or ornamental piece 3, which may be a stone or a shield of metal having some fanciful characteristics, for ex-

ample, such as a signet ring. The head or ornamental portion 3 is provided with a lug 4 near one end, which lug extends into an opening 5 provided in the enlarged portion 2. A pin 6 is extended transversely through the setting 3 and lug 4 and hingedly connects the setting 3 with the ring. In the opposed faces of the setting 3 and portion 2 there are provided knives 7 arranged opposite one another and provided with beveled or rounded cutting edges 8 which form a V space in which the cord or string to be cut as shown at 9, may be inserted in order to sever the same (see Figs. 5 and 6).

As a means for holding the head 3 raised so that the string may be brought into engagement with the knives, a small leaf spring is fastened as at 10 to the portion 2 and bears on the head 3 so as to force the free end of the same upwardly. When the head is in raised position, the knives are substantially concealed and upon ordinary inspection of the ring when it is worn on the hand, it has the same appearance as the ordinary ring. However, when it is desired to sever a string it is only necessary to bring the string in between the knives to effect a cutting or severing action. It will thus be seen that the ring will be highly useful to bundle wrappers and clerks who are required to tie bundles and packages.

In order to cause the setting to lie flat on the ring and to better conceal the cutting arrangement so that the ring will appear more like the ordinary finger ring, there is provided a cam or wedge member 11 which is pivoted as at 12, to the enlarged portion 2 and when the ring is ready for use as a cutter projects outwardly a slight distance. By engaging this projecting portion of the wedge member 11 and moving the same so that it wedges between the members 2 and 3 near the pivoted ends of the latter, the member 3 will be moved so that it is caused to lie flat against the member 2, the knives then overlapping one another. To release the setting so that it will move by action of the spring into open position and permit of access to the cutters, it is only necessary to remove the wedge or cam member from between the members 2 and 3, there being a portion of said member projecting slightly from the margin of the head whereby it may be readily engaged with the finger nail and moved as described.

It will thus be seen that I have provided

a highly useful, simple and compact ring which takes into consideration the provision of an ornamental setting, such as a stone or metal shield, between which and the body 5 of the ring an effective cord cutter is arranged and in which the setting may be moved into and out of a position providing for access to and well concealing the cutter.

I claim:

- 10 1. A ring comprising a body portion, a setting hinged adjacent one end to the body portion, a knife located between the setting and body portion and arranged to be accessible when one end of the setting is raised.
- 15 2. A ring comprising a body portion, a spring at all times tending to raise said end of the setting and means for moving and holding the setting in position flat against the ring body portion and preventing access to the cutter, said setting sub-

stantially concealing the knife and its associated elements. 20

2. A ring comprising a body portion, a setting hinged adjacent one end to the body portion, a knife located between the setting and body portion and arranged to be accessible when one end of the setting is raised, 25 a spring at all times tending to raise said end of the setting and means for moving and holding the setting in position flat against the ring body portion and preventing access to the cutter, which means comprises a wedge member pivoted on the body portion and movable to engage between and with the body portion and said setting, 30 said setting substantially concealing the 35 knife and its associated elements.

YAICHIRO SHIBA.
